tion of Missouri

Application September 9, 1937, Serial No. 162,989

7 Claims. (Cl. 229—55)

This invention relates to bags generally, and with regard to certain more specific features, to multi-ply, paper bags.

Among the several objects of the invention may be noted the provision of multi-ply paper bags which, despite the fact that they are formed of paper which is itself flexible, present when filled a rigid appearance resembling that of pasteboard or cardboard boxes, cartons, or the like; the provision of a paper bag of the class described which is not likely to bulge or become curved in its contours when it is filled; the provision of a paper bag of the class described, which, while it is formed of flexible materials, is provided with relatively stiffened or rigid regions, which regions, however, are disposed so as not to interfere with the proper folding of the bag, as for filling the same; the provision of a bag of the class described which is readily closed and sealed; and the provision of a bag of the class described which is relatively simple and economical to manufacture. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which are illustrated several of various possible embodiments of the invention,

Fig. 1 is a plan view of a bag blank, one of the plies of the blank being in part laid aside to show the interior construction;

Figs. 2, 3 and 4 are enlarged cross-sections taken substantially along lines 2—2, 3—3 and 4—4, respectively of Fig. 1;

Fig. 5 is a plan view of the blank of Fig. 1, after a tubing operation has been performed thereon;

Fig. 6 is a plan view of the blank of Figures 1 and 5 after a bottom-forming operation, and represents a completed bag prior to the filling and closing thereof;

Fig. 7 is an isometric view of a filled bag made in accordance with the present invention, showing the closed top of the bag;

Fig. 8 is an isometric view similar to Fig. 7, but showing the closed bottom of the bag;

Fig. 9 is a plan view of a blank for another embodiment of the invention;

Fig. 10 is a plan view of the reverse side of the blank of Fig. 9;

Fig. 11 is a plan view of a blank of still another embodiment of the invention; and,

Fig. 12 is an isometric view of a filled, closed bag made from the Fig. 11 type of blank.

Similar reference characters indicate corresponding parts throughout the several views of the drawings. Throughout the several views of the drawings, relatively long dashed lines are used to indicate fold lines, while relatively short dashed lines indicate invisible edges, etc. Stippling is used to indicate adhesive areas.

An objection to paper bags for material packaging, particularly such materials as are dispensed in relatively small, household quantities, has always been that said bags bulge into ovate and similar rounded forms when they are filled. Bulging bags of this character not only fail properly to display the printed legends thereon, but are also difficult to handle on stock shelves and are difficult to package in larger containers, as for shipment. Furthermore, such bags, as the contents are used therefrom, have a tendency to collapse as progressively more of the contents are removed.

It is a primary object of the present invention to provide a paper bag, which, although it is made of the flexible materials ordinarily employed in bag manufacture, it is nevertheless so strengthened in predetermined areas thereof, that the finished bag, when filled, exhibits the rigid, rectangular, non-bulging characteristics of a pasteboard or light cardboard box or carton, and which, furthermore, does not collapse as the contents are progressively removed therefrom.

Generally speaking, this object is accomplished in the present invention by making a bag of a multi-ply construction, with predetermined relatively large areas of stiffening adhesive positioned between the plies in such manner that, when the bag is finally folded up and filled, said stiffened areas constitute the bounding walls of the bag.

It has heretofore been proposed to use areas of stiffening adhesive in connection with the mouth portions of multi-ply paper bags. See, for example, the patent of Louis J. Finn and Arnold N. Weeks, No. 2,092,602, dated September 7, 1937. However, in no case of which I am aware has an adhesive region been used for stiffening the front, back, and sides of a paper bag.

Referring now more particularly to Fig. 1, there is illustrated a blank for making up a paper bag in accordance with the present invention. The blank is of multi-ply construction, comprising, in the embodiment illustrated, a rectangular sheet 1, which is to become the outer or covering surface of the bag, and a superimposed rec-

tangular sheet 2 which is to become the inner surface of the bag. The sheets 1 and 2 are adhesively secured together by means of adhesive material applied at predetermined areas, more fully to be described hereinafter. It is to be understood, however, that both sheets 1 and 2 are relatively flexible paper material, such as is customarily used for bag-making purposes, and are not pasteboard or cardboard or other rigid materials of the type ordinarily used for making cartons or boxes. For greatest economy of manufacture, it is advisable that the outer sheet 1, which is the paper sheet that will be displayed in the finished bag, be of a relatively lightweight character, while the inner sheet 2 may be made heavier in order to provide the necessary strength for the composite blank. This is because the outer or exposed paper is usually of a much more expensive character than the inner or liner paper, which may ordinarily be of a relatively cheap character. For example, I have satisfactorily used for the outer layer, a finished paper of thirty-pound weight, while the inner layer is a sixty-pound kraft material, of a relatively cheap character.

In assembling the two layers 1 and 2 together in multi-ply arrangement, the lateral edges of the two sheets are somewhat displaced in order to provide overlap regions. Numeral 3 indicates the region where the outer paper ply 1 overlaps the inner paper ply 2, while numeral 4 similarly indicates the overlap of the inner paper ply 2 over the outer paper ply 1. As will appear hereinafter, the overlap 4 is not absolutely necessary. That is to say, one overlap is enough to accomplish the desired end. It is to be understood that the term overlap herein is synonymous with the term extension. That is, the overlaps 3 and 4 are also in the nature of extensions.

From the lower edge of the composite blank, at a predetermined suitable location, extends a semi-circular tab 5, which is desirable in order that the bag may be folded and formed in certain available bag-making apparatus, such as the type shown and described, for example, in Belcher et al. Patent 2,088,228 dated July 27, 1937. As the blanks in question are ordinarily cut successively from relatively endless webs of paper, the semi-circular tab 5 from the preceding blank provides a notch of semi-circular contour, indicated by numeral 6, in the top edge of each succeeding blank. The notch 6, however, is without particular utility in connection with the blank of the present invention.

It will be understood that the exact form of tab is unimportant in the present invention, and that it may even be entirely eliminated, as in the case of bags made on certain machinery which does not require it for the folding operations.

Fold lines, which may or may not actually be present in the blank as it is commercially manufactured, or which may comprise merely suitable indicating marks on the blank, are provided to divide the blank into a plurality of separate panels or regions.

Numeral 7 indicates a front panel, which is bounded at its sides by fold lines 8 and 9 extending from the top to the bottom of the blank, at its top by a fold line 10 which extends from side to side of the blank, and at its bottom by fold line 11, which likewise extends from side to side of the blank. Numeral 12 similarly indicates a back panel, which is bounded at its sides by fold lines 13 and 14, extending from top to bottom of the blank, at its top by fold line 10, and at its bot-

tom by fold line 11. The front 7 and back 12 are interchangeable, it will be understood, and either panel 7 or 12 may be the front or back of the finished bag. A rectangular panel 15, bounded at its side by the fold lines 9 and 13, and at its top and bottom by the fold lines 10 and 11, respectively, constitutes one side of the bag, and is centrally divided by a fold line 16, which extends from the top to the bottom of the blank. The panel 17, which is bounded at its sides by the fold line 14 and the right-hand edge 18 of the blank, and at its top and bottom by its fold lines 10 and 11 respectively, constitutes the other side of the bag, and is likewise centrally divided by a fold line 19 extending from the top to the bottom of the blank. The panel 20, which is bounded at its side by the fold line 8 and the left-hand edge 21 of the blank, and at its top and bottom by the fold lines 10 and 11, respectively, is about one-half the width of a side of the bag, and, in the assembled bags, overlaps and is secured to a part of the side panel 17.

All material in the blank above the fold line 10 ultimately forms the top closure of the bag, while all material of the blank below the fold line 11 similarly forms the bottom closure of the bag. Among the elements or portions going to form the top closure of the bag may be noted the rectangular panels 22 and 23, respectively surmounting the front panel 7 and back panel 12 of the blank. The panel 22 is bounded by the upper edge of the blank, and by the fold lines 8, 9 and 10, while the panel 23 is similarly bounded by the upper edge of the blank, and by the fold lines 10, 13 and 14. Intersecting diagonal fold lines 24 and 25 extend across each of the panels 22 and 23, from the respectively lowermost corners thereof, adjacent the fold line 10. To the left of the panel 22 is a relatively small panel 26, which is bounded by the top edge of the blank, the lateral edge 21 of the blank, and the fold lines 8 and 10. Between the panels 22 and 23, is a substantially square-shaped panel 27, through the center of which runs the fold line 16. The panel 27 is bounded by the upper edge of the blank and by the fold lines 9, 10 and 13. To the right of the panel 23 is a substantially square panel 28, which is centrally divided by the fold line 19. The panel 28 is bounded by the upper edge of the blank, the lateral edge 18 of the blank, and by the fold lines 10 and 14.

It is to be understood that the intersecting character of fold lines 24 and 25 is only incidental to the particular bag disclosed, and that the invention may be carried out with non-intersecting lines at this point.

The lower or bottom closure of the bag is made up of panels lying below the fold line 11 in Fig. 1. Among these panels, numerals 29 and 30 indicate rectangular panels that respectively underlie the front panel 7 and back panel 12 of the blank. Panel 29 is defined by the lower edge of the blank, and by parts of the fold lines 8, 9 and 11, while panel 30 is similarly defined by the lower edge of the blank, and by the fold lines 11, 13 and 14 (Fig. 1). A pair of slots 31 are provided in each of the panels 29 and 30, said slots running perpendicularly inwardly from the lower edge of the blank to the fold lines 36, 37, 38 and 39. A tab 32 is thus provided in the panel 29 between the pair of slots 31 therein, while a similar tab 33 is likewise provided in the panel 30. A fold line 34 extends across the tab 32, parallel to the lower edge of the blank, and a similar fold line 35 is provided in the tab 33.

A diagonal fold line 36 extends from the upper end of left-hand slot 31 in panel 29, through the point of intersection of fold lines 8 and 11, to the left-hand edge 21 of the blank. From the inner end of the right-hand slot 31 in panel 29 extends, diagonally, a fold line 37, which intersects the point of intersection of fold lines 9 and 11, and which terminates at the fold line 16. A similar diagonal fold line 38 extends from the inner edge of left-hand slot 31 in panel 30, through the intersection of fold lines 11 and 13, to a point on the fold line 16, where it intersects the diagonal fold line 37. Still another diagonal fold line 39 extends from the top of the right-hand slot 31 in the panel 30, through the intersection of fold lines 11 and 14, to terminate at the fold line 19. A final diagonal fold line 40 extends down and away from the point of intersection of fold lines 39 with the fold lines 19 at an equal angle to that made by the fold line 39, and terminates at the right-hand edge 18 of the blank.

The manner in which adhesive is applied between the plies 1 and 2 of the blank, as heretofore intimated, is one of the principal features of the present invention. A broad area 41 of adhesive, for example, is positioned between the two plies in the region of the front panel 7. The area 41 extends, at its top, all the way to the fold line 10, but the area 41 terminates just short of the fold lines 8, 9 and 11, thus providing narrow regions 42, 43, and 44, respectively, between the adhesive area 41 and respective fold lines 8, 9 and 11, which are free of adhesive and thus merely two plies of flexible paper held in juxtaposition.

Numeral 45 indicates a similar broad adhesive area, which is positioned between the plies of panel 20, and which extends from the fold line 10 downwardly almost to the fold line 36, and laterally from the left-hand edge of ply 1 almost to the fold line 8. From the area 45, a narrow stripe 46 extends upwardly along the edge of the ply 1 to the top of the blank, and a similar stripe 47 extends downwardly along the edge of the ply 1 through substantially the entire vertical length of the panel between the fold lines 8 and 11. The stripe 47 at its lower end turns sharply to the right, as indicated at numeral 48, and extends along the bottom edge of the blank, albeit spaced therefrom a short distance, to a point just short of the fold line 8.

An adhesive area 49 is provided between the plies 1 and 2 of the left-hand portion of panel 15, extending from a position close to the fold line 9 to a position close to the fold line 16, and from the fold line 10 to a position close to the fold line 37. A similar, but oppositely faced adhesive area 50 is provided between the plies 1 and 2 of the right-hand portion of the panel 15, between fold lines 16 and 13. An adhesive area 51 is provided between plies 1 and 2 of the back panel 12, and extends from near the fold line 13 across to near the fold line 14, and from the fold line 10 down to near the fold line 11. The left and right-hand portions of panel 17 are provided with adhesive regions 52 and 53, respectively, which are similar in shape to the adhesive regions 49 and 50, and which similarly terminate, laterally, just short of the fold lines 14 and 19 (and the lateral edge of ply 2), and longitudinally at the fold line 10 and just short of the fold lines 39 and 40, respectively. From the adhesive region 53, a stripe 54 of adhesive extends vertically upwardly to the top edge of the blank, while a stripe 55 extends downwardly from along the right-hand edge of ply 2, almost to the bottom

of the blank. The stripe 55 then turns sharply to the left, as indicated at numeral 56, to terminate just short of the fold line 19. The stripe portions 55 and 56 are thus similar, but oppositely faced, to the striped portions 47 and 48 at the left-hand side of the blank.

Extending across the bottom of the blank, but spaced therefrom at a short distance, are a series of disconnected spots of adhesive. Numeral 57 indicates a small spot of adhesive that is positioned along the lower edge of panel 29, to the left of the left-hand slot 31. Numeral 58 indicates a spot of adhesive that is positioned in the panel 29, between the right-hand slot 31 and the fold line 9. Numerals 59 and 60 indicate short stripes of adhesive that are positioned along the lower edge of the blank between fold lines 9 and 16, and 16 and 13, respectively, terminating just short of said fold lines. Numeral 61 indicates a spot of adhesive that is positioned between the fold lines 13 and the left-hand slot 31 in panel 30. Numeral 62 indicates a spot of adhesive that is positioned between the right-hand slot 31 and the fold line 14, along the lower edge of panel 30. Numeral 63 indicates a short stripe of adhesive that extends along the lower edge of the blank between the fold lines 14 and 19, terminating just short of said fold lines.

Between the plies of the tab portions 32 and 33 of panels 29 and 30, respectively, there are positioned rectangular frame-shaped areas of adhesive indicated respectively by numerals 64 and 65. The frames 64 and 65 terminate just short of their respective slots 31, and include non-adhesive regions 66 and 67, respectively, which extend on either side of the fold lines 34 and 35.

The adhesive used for the several adhesive regions heretofore described should be of such a character that it firmly adheres the two plies together, and in addition sets up so that the blank, in the respectively adhesived regions, is relatively as rigid as a pasteboard, or light cardboard. For convenience, the same adhesive is used at the regions 64 and 65 (in the bag bottom) as is used for stiffening the sides, but it is to be understood that if this point of convenience be waived, it might be preferable that this adhesive be of a different nature, as for instance a more flexible adhesive.

In order to prevent the two plies 1 and 2 from coming apart along the length of the top edge of the blank, it is preferable to provide a number of small spots 68 of adhesive near said top edge.

By reference to Fig. 1, it will be seen that in substantially no instance does a large adhesive area extend across a fold line. On the contrary, the adhesive areas are, in general, stopped short of fold lines, so that fold lines are located along the flexible, non-adhesive portions of the plies 1 and 2. This facilitates later folding of the blank to a finished bag.

The paste or adhesive may be applied to one or the other of the plies in assembling the multiply blank either manually, or by any suitable automatic means, such as a rotary cylinder resembling a printing press cylinder, having raised portions corresponding to the various areas to be provided with adhesive. In such a procedure, the adhesive is applied to one of the plies, and the other ply is then juxtaposed to the adhesived ply, and the composite structure passed between a pair of pressing rollers or other suitable mechanism to provide for firm, smooth adherence between the plies.

After the blank has been prepared in the man-

as illustrated in Fig. 1, it is next folded into a tube, the operation being termed "tubing" the blank. Usually said tubing is accomplished by automatic machinery available for this purpose. The tubing is brought about by folding the blank along the fold line 16, with the liner ply 2 on the inside, thus positioning the left-hand edge 21 of the blank over the fold line 19. The right-hand edge of the blank is then folded back on the already folded blank along fold lines 19, so that the right-hand portion of panel 17 overlaps the panel 20. A suitable adhesive (not shown in the drawing) is applied between the right-hand portion of panel 17 and panel 20, in order to secure the blank in tubular form. As thus made up into a tube, the blank assumes the form illustrated in Fig. 5. By reason of the overlapping end portions 3 of the cover ply 1, said cover ply provides a clean joint on the outer surface of the bag.

The next step in forming the bag comprises subjecting the tubular blank of Fig. 5 to a series of bottom-forming operations, which are described in detail in Belcher et al. Patent 2,088,228, dated July 27, 1937. Broadly, this operation comprises collapsing inwardly, along diagonal fold lines 36, 37, 38 and 39, the two lower corners of the tubular blank, as indicated in Fig. 5 by numerals 69 and 70, and thereafter juxtaposing, and pasting together the two tabs 32 and 33 of the bottom panels 29 and 30. Since the sequence of operation for forming the bottom in this manner is described in great detail in the aforesaid Belcher patent, it is not repeated herein. After the bottom is thus formed, the blank has the appearance shown in Fig. 6, in which condition it is ready to receive the material to be contained therein. In general, bags according to the present invention are supplied to the packager in the form illustrated in Fig. 6.

For use, the bag is first brought to rectangular form by expanding it from the Fig. 6 form. This expanding is performed by flattening the side folds 16 and 19 and at the same time bringing the corner folds 8, 9, 13 and 14, to right-angular positions, meanwhile pressing out the bottom corners of the bag to complete the rectangular shape by folding said corners along fold lines 11 and at the same time flattening the proper portions of diagonal fold lines 36, 37, 38, 39 and 40. As thus expanded, the bag has a rigid, rectangular shape provided by the rigid, reenforced front and back panels 7 and 12, respectively, and the rigid, reenforced side panels 15 and 17. The bag is now filled through the open top thereof. The rigidity of the adhesively reenforced panel is such that, as it is filled, the bag undergoes no bulging whatsoever, but retains its regular shape.

After the bag as thus described has been filled, the top is closed in a more or less usual manner by first collapsing in the sides of the top, constituting panels 27 and 28, by folding them inwardly along horizontal fold line 10 and respective diagonal fold lines 24 and 25, and thereafter by folding down the triangular remaining portions of panels 22 and 23 in overlapping arrangement. The closure as thus provided is illustrated in Fig. 7, while Fig. 8 similarly shows the disposition of the various portions at the bottom of the bag, when the bag is in its filled condition. The top closure means are secured together, of course, by means of properly applied adhesive material.

The thus-completed, filled bag is a rigid structure, fully resembling a box or similar container

rather than a bag. At the same time, it has all of the advantages of bags as contrasted with boxes.

In order to facilitate folding down the top of the finished bag, in making the top closure, it is advisable that the fold line 10 actually be a score line as indicated in Fig. 4, which is an enlarged cross-section indicated by the numeral 10.

Numerous modifications are possible within the scope of the present invention. For example, in Figs. 9 and 10 is shown a form of blank which is alternative to the blank of Fig. 1. The principal distinction of the blank of Figs. 9 and 10 is that the adhesive areas are, respectively carried directly up to and over the several fold lines, rather than terminating short thereof as in the Fig. 1 embodiment. In order, then, to provide for ready folding in the proper locations, the blank is provided with a plurality of score lines indicated generally in Fig. 10 by numeral 72, which score lines overlie their respective fold lines and thus break down the adjacent adhesive and make the blank properly foldable at the proper location, when it is formed into a bag. An advantage of the embodiment of Figs. 9 and 10 over the embodiment of Fig. 1 is that the corners of the finished, filled bag are more rigid (longitudinally considered), as they are reenforced in the same manner as the front, back and sides of the bag. Thus the corners act as relatively free hinges.

In the embodiment shown in Fig. 11, a different form of top closure is disclosed. In this embodiment, the adhesive, which is similar to the embodiment of Figs. 9 and 10 insofar as the extension of the adhesive over the fold lines is concerned, is continued clear to the top of the bag blank, thus providing for reenforcement of the top, as well as the front, back and sides of the bag. The diagonal fold lines 24 and 25 are omitted from this embodiment, and instead there-of there are provided a series of slots 73 extending perpendicularly inwardly from the upper edge of the blank to the fold line 10. These slots 73 respectively, relieve the panels 22, 23, 26, 27 and 28 from each other. After the blank of Fig. 11 has been tubed and the bottom formed in the manner heretofore described, and the bag has been expanded and filled, the top closure is effected first by bending in the panels 27 and 28 along these fold lines 10, and then on top thereof in overlapping relation, folding in the panels 22 and 23. The resultant closure is similar to that in current use for pasteboard boxes and the like, and is shown in completed form in Fig. 12. Ordinarily, this closure is not as leak-proof as is the closure disclosed in the previous embodiments, but with the addition of a suitable insert material, such as a properly folded sheet of waxed paper, it may satisfactorily be used for the packaging of many types of materials.

It will be seen that each of the plies used in all forms of the invention continues around the girth of the bag. This provides substantial girth strength while at the same time satisfactory hinge characteristics inhere. Also, the folded top and bottom closures are formed from plies which are continuous with the plies in the girth portion of the bag, and thus further add to the strength by reason of the integralness of the various plies.

In all of the embodiments of the invention disclosed, the liner paper may, for certain purposes, be made of a water-, grease-, or oil-proof character. Furthermore, this liner paper may itself be multiple-ply; that is, the layer or ply which is shown and indicated by numeral 2 in Fig. 1, may

itself be made up of two or more plies, adhesively or otherwise united.

In this application it is intended that the reference to stiffening substantially the entire front, back and sides of the bag shall include cases where stiffening is enough to preserve a box-like or carton-like structure, regardless of how much material may be removed for superficial purposes, such as placement in the fronts, backs and sides 10 of flexible Cellophane windows, indicator slots, pouring spouts, or the like.

It is considered that at least one important feature of the invention is in the fact that said front, back and sides of a bag are sufficiently 15 stiffened to give the carton-like appearance and function when filled, without the disadvantages of providing such a carton, and this feature will inhere even with the use of relatively small areas 20 of flexible windows, bands, or the like, which do not defeat the stiffening functions of the stiffened areas herein referred to.

The invention applies to various types of bags. For example, the bags shown employ edge constructions which extend outwardly when the bag 25 is unfilled, whereas the invention also applies to bags wherein the edge constructions are formed as inward, intucked gussets when the bag is unfilled. Other adaptations of the invention will be obvious to one skilled in this art.

30 In view of the above, it will be seen that the several objects of the invention are achieved and other advantageous results attained.

As many changes could be made in carrying out the above constructions without departing 35 from the scope of the invention, it is intended that all matter contained in the above description or shown in the accompanying drawings shall be interpreted as illustrative and not in a limiting sense.

40 I claim:

1. A multi-ply bag comprising relatively flexible individual plies, said bag having a rectangular form when expanded, providing a front panel, a back panel and side panels, each ply being continuous around the girth of the bag, areas of 45 stiffening adhesive between the plies substantially through the entire areas of said front, back and side panels, and folded top and bottom closures for said bag, said closures being provided with flexible, and foldable regions in suitable locations 50 for folding the closures to closing positions and being formed from plies which are also continuous with the plies in the girth portion of the bag.

2. A multi-ply bag comprising relatively flexible 55 individual plies, said bag being made from a tubular form and comprising a front panel, a back panel, side panels between said front and back panels, said plies each being continuous around the girth portion of that part of the tubular form which provides said front, back and side panels, a bottom closure, and a top closure, said closures being formed from plies which are continuous with the plies of the girth portion, fold lines between all of the adjacent panels and 60 additional fold lines substantially in the centers of the side panels and parallel to said first-mentioned fold lines, and stiffening adhesive between the plies of said bag and extending substantially throughout the areas of each of said panels, but 65 stopping just short of the fold lines mentioned, whereby said fold lines occur along regions of non-adhesively-stiffened, flexible ply material.

3. A multi-ply bag comprising relatively flexible individual plies, said bag being made from a tubu-

lar form and comprising a front panel, a back panel, side panels between said front and back panels, said plies each being continuous around the girth portion of that part of the tubular form which provides said front, back and side panels, a bottom closure, and a top closure, said closures being formed from plies which are continuous with the plies of the girth portion, fold lines between all of the adjacent panels and additional fold lines substantially in the centers of the side 10 panels and parallel to said first-mentioned fold lines, and stiffening adhesive between the plies of said bag and extending substantially throughout the areas of each of said panels, each of said fold lines comprising score lines in at least one of said 15 plies, said adhesive extending across said fold lines.

4. A multi-ply bag comprising a plurality of relatively flexible individual plies comprising a front panel, a back panel, and side panels, a closed bottom closure, and an open top closure, all plies of each front, back or side panel being continuous with the plies of said bottom and top closures, and stiffening adhesive between at least two of the plies substantially throughout the 20 entire area of said front, back and side panels, said panels being relatively hinged whereby a 25 carton-like appearance is effected upon filling, said bottom closure being left flexible enough to permit the bag to lie flat and folded while empty. 30

5. A multi-ply bag comprising a plurality of relatively flexible individual plies, said bag being made of a tubular form comprising a front panel, a back panel, side panels between said front and back panels, a closed bottom closure, and an open 35 top closure, all plies of the front, back or side panels being continuous with the plies of said bottom and top closures, areas of stiffening adhesive between at least two of the plies substantially 40 throughout the entire areas of said front, back and side panels, said bottom and top closures having only relatively limited areas of adhesive between plies therein.

6. A multi-ply bag comprising a plurality of relatively flexible individual plies, said bag being 45 made of a tubular form comprising a front panel, a back panel, side panels between said front and back panels, a closed bottom closure, and an open top closure, all plies of the front, back or side panels being continuous with the plies of said bottom and top closures, areas of stiffening adhesive between at least two of the plies substantially 50 throughout the entire areas of said front, back and side panels, said bottom closure having at most a relatively limited area of adhesive between 55 plies which areas do not substantially interfere with its flexibility, whereby the bag may be shipped flat with a closed bottom.

7. A multi-ply bag comprising a plurality of relatively flexible individual plies, said bag being 60 made of a tubular form comprising a front panel, a back panel, side panels between said front and back panels, a closed bottom closure, and an open top closure, all plies of any front, back or side panel being continuous with the plies of said bottom and top closures, areas of stiffening adhesive 65 between at least two of the plies substantially throughout the entire area of said front, back and side panels, and throughout substantially the entire area of the top closure, but being positioned throughout only limited portions of the 70 area of said bottom closure.
